UNITED STATES PATENT OFFICE.

JACOB S. BRETZ, OF NEW YORK, N. Y.

DESIGN FOR A WHEEL-HUB.

SPECIFICATION forming part of Design No. 23,742, dated October 23, 1894.

Application filed February 3, 1894. Serial No. 499,033. Term of patent 7 years.

To all whom it may concern.

Be it known that I, JACOB S. BRETZ, a citizen of the United States, and a resident of the city of New York and State of New York, 5 have invented a certain new and original Design for Wheel-Hubs, of which the following is a full, clear, and exact description, reference being had to the accompanying drawing, forming part of this specification.

10 My invention has relation to a design for wheel-hubs, and consists in the new and original shape or configuration of hub for wheel, as hereinafter particularly described and illustrated in the drawing.

15 The accompanying drawing is a perspective view of my design of wheel-hub.

At either end of the rounded sleeve, A, longitudinally disposed is an enlarged disk, B, B', and from the periphery of each disk 20 radiate small sections or blocks giving the

appearance of abbreviated or sawed-off spokes. On the outer end of each enlarged disk are provided a ring and angular edged protrusion of less diameter than the enlarged disk. The effect of the whole is that of an imitation wooden hub, is pleasing to the eye, and produces an ornamental shape or configuration.

Having thus described my invention, what I claim, and desire to secure by Letters Patent, is—

The design for a wheel-hub substantially as described and as illustrated in the accompanying drawing.

In witness whereof I have hereunto set my hand this 31st day of January, A. D. 1894.

JACOB S. BRETZ.
